UNITED STATES PATENT OFFICE

129,500

DESIGN FOR A TOY BOAT

Joseph K. Weddell, Springfield, Mass., assignor to Milton Bradley Company, Springfield, Mass.,
a corporation of Massachusetts

Application May 28, 1941, Serial No. 101,209

Term of patent 3½ years

To all whom it may concern:

Be it known that I, Joseph K. Weddell, a citizen of the United States, residing at Springfield, in the county of Hampden and State of Massachusetts, have invented a new, original, and ornamental Design for a Toy Boat, of which the following is a specification, reference being had to the accompanying drawing, forming part thereof.

Fig. 1 is a side elevational view of a toy boat showing my new design; and

Fig. 2 is a plan view of the boat shown in Fig. 1.
The side of the boat opposite to that shown in Fig. 1 has the same appearance.

I claim:

The ornamental design for a toy boat, as shown and described.

JOSEPH K. WEDDELL.
